UNITED STATES PATENT OFFICE.

SAMUEL L. LAZARON, OF SAVANNAH, GEORGIA.

PENCIL-HOLDER.

SPECIFICATION forming part of Letters Patent No. 513,239, dated January 23, 1894.

Application filed May 6, 1893. Serial No. 473,281. (No model.)

To all whom it may concern:

Be it known that I, SAMUEL L. LAZARON, a citizen of the United States, residing at Savannah, in the county of Chatham and State 5 of Georgia, have invented certain new and useful Improvements in Pencil-Holders; and I do hereby declare the following to be a full, clear, and exact description of the invention, such as will enable others skilled in the art to 10 which it appertains to make and use the same.

My invention relates to pen and pencil cases, and is an improvement on the invention shown and described in my application for Letters Patent, Serial No. 450,078, filed 15 October 26, 1892, patented April 25, 1893, and numbered 495,980.

My present improvement although adaptable for application to pen and pencil cases can also be attached to many other devices, 20 such as walking-canies, umbrellas, handles of various articles, paper-weights, slate-frames, &c., all as hereinafter fully described, illustrated in the drawings, and specifically pointed out in the claims.

25 Referring to the accompanying drawings, wherein like letters and figures of reference point out similar parts on each view:—Figure 1. represents my invention applied to a holder for a removable pen and pencil. Fig. 2. is a like 30 view showing the pen and pencil in reversed position, whereby the inscribing points are protected when not in use, the inclosing tube being partly broken away, showing interior construction. Fig. 3. is a detail view of the

35 spool removed from its inclosing case, representing one form of inner actuating spring and method of its connection to end disks. Fig. 4. is a view with the device connected to the frame of a slate. Fig. 5. is a view of the 40 device attached to a walking cane, portions being broken away. Fig. 6. represents application of the device to the roller of a map or window shade. Figs. 7, and 8. are detail views of parts of the device detached from

45 the escapement. Fig. 9. represents solid springs for inclosing within interior spool and means for its connection to end disks. Fig. 10. is a sectional view of the incasement on a reduced scale. Fig. 11. is a view of the 50 device provided with a swinging cover having a lengthwise slot for passage of ribbon therethrough.

In the drawings:—A, is a tubular case with open ends, a, into which can be inserted a pencil or crayon, 1, or pen, 2, which can be 55 removed, or their position reversed, so as to expose their butt ends, and enable the case, with such connections, to be handled or carried in the pocket, without exposing the inscribing points, as plainly illustrated in Fig. 6c 2. At desired distances the case, A, has circumferential inverted grooves, 3,—4,—which in some instances are not of equal depth, for a purpose presently set forth. Said grooves divide the case into end sections, x, x, and 65 middle section, x'.

Within section, x', is placed the operative members of the device, as hereinafter described, said section having a longitudinal slot, 5, through which one or more inscribed 70 ribbons, B, B' are free to pass inwardly and outwardly of case A.

C, is a revoluble hollow spool, having end flanges, c, c, centrally apertured in alignment with axis of the spool. At the median point 75 of said spool is preferably, an orifice, c', whereby the inscribed ribbons may be directly connected to spring inclosed within the spool. Said spring may be a continuous loop of rubber D, or a single length, D', as shown 80 and described in my invention, upon which this specification is an improvement thereof having central orificed enlargement, d, and transverse extensions, d', at either end.

The spring, D', may be of any desired form 85 in cross section, several forms being illustrated in Fig. 9, it being preferable that when such band is made of solid rubber its outer surface should be not of uniform plane, but have channels, grooves or corrugations which 90 construction, as will be readily understood, will increase its elasticity and resiliency when subjected to tension and released therefrom. Said spring is inserted lengthwise within spool, C, passing through apertures of its end 95 flanges and in practice the opposite terminals thereof are fastened to disks, C', made of metal, wood, or other rigid material. Said disks have inwardly inclined grooves, c², extending the full depth of periphery thereof, 100 into which the ends of springs, D, D', fall when passed over said disks, and in which recesses, c², the springs will be securely maintained, as the device is operated. Spool, C,

is inserted within open end of the tube and will readily pass therein. In adjusting the spool within the case, its inclosed spring is first stretched lengthwise by means of a hook, 5 thread, or wire temporarily connected at each end thereof. The spool is then passed into tubular case, A, and deposited within the section, α' , the opposite ends of spring within the spool, C, are then respectively connected to a retaining disk, C', the spring is then released from extension and the attached end disks sprung within the case until reaching grooves, 3,— 4,— which limit their further progression and thus maintain the spring in 15 position for operation. The ribbons are adjusted to the spring by a small inflexible loop, b, which is threaded through orifice at inner edge of said ribbons and from thence directly connected to the spring. If the spring is 20 formed of a continuous length, D, said loop is passed over one of the strands, if a band, D', said loop, b, is threaded through aperture in enlargement, d. Said loop, b, that connects the ribbons to spring within the spool passes 25 outwardly through orifice, c'. It is however preferable that it shall also be turned once around barrel of spool, C.

A single length of ribbon may be folded upon itself to make two layers, B, B'. The 30 fabric composing said ribbons may be returned upon itself and the loop, b, in that instance, be passed through folded overturned which will add strength to the connection of ribbon to said loop.

35 The disks, C', as hereinbefore set forth are preferably provided with opposite grooves, c², to receive end of the spring which will sink therein and maintain the spring extended lengthwise. Disks so conformed when slid 40 into the tube A, will engage the grooves, 3,— 4,—.

I do not desire to limit myself to this special means for connecting the spring, to disks, C', as other forms thereof may be employed 45 without departing from the scope and purview of my invention.

In Fig. 9, the spring is shown as a band, having end bead flanges, and disk, C', provided with central aperture into which the 50 beaded end flange can be sprung, and when passing outwardly therefrom will be in position shown in said figure. To prevent any possibility of the spring turning, a pin or other clasp may be employed to hold ends of 55 spring securely to the end disks.

It is my intention to have one or more encyclopedia ribbons adjusted to be automatically drawn into, and be withdrawn from tubular incasement A, as fully described in the 60 device, to which the present invention is an improvement and to leave uninscribed space or spaces on the surface for reception of postage stamps, to be thereat retained by adherence of edge thereof to said location, it being understood that the stamps will be protected 65 from abrasion or rupture by lying interme-

diately of the superimposed lamina of fabric composing the ribbon.

The ribbons may be connected in any desirable manner, or they may be composed of 70 a single length of fabric folded over forming two leaves the overturned fold provided with a slot or aperture for reception of loop, b, for connection to spring within spool, C, in manner and form hereinbefore set forth. Another 75 means of retaining postage stamps or removable memoranda for temporary use, a pocket, P, may be attached to the inner surfaces of one of the ribbons as plainly illustrated in the drawings. I deem this a novel and useful improvement on devices of analogous character. The pocket, P, besides being employed for deposit of postage stamps is also adapted for reception of slips of paper with memoranda of addresses or other matter for temporary use. 85

I have thus far confined description of my invention to employment of two overlying ribbons, but I do not desire to limit myself thereto; for some articles, but a single one may be necessary while for others it is my intention to employ a number in excess of two, according to the structure of the device to which my invention is adaptable, whereby I am enabled to largely increase the surface area, for reception of inscriptions, calendars, 90 advertisements, and other suitable subjects of information.

The case with its inclosure, as illustrated, in Figs. 1,— and 2,— is adapted to be carried in the pocket without risk of disarrangement 100 of any of its operative connections.

When desired to be inclosed in a cane, or any other article, such as shown in Figs. 4,— 5,— and 6,— it is my intention to employ a number of sheets of ribbons, upon which to display inscriptions of many characters such as 105 calendars, arithmetic indicia, advertisements, and other subjects of information, including spaces or pockets for postage stamps and removable memoranda, in which case the overlying ribbons will be connected at their inner ends with a binding strip, b', to which loop, b, will be passed in manner and form hereinbefore described. It is preferable when a 110 multiple of ribbons are employed that they be wound around the spool concentrically before it is inclosed within tubular incasement, A.

Figs. 10 and 11, represent the device adapted to receive a number of ribbons which can 115 be drawn outwardly and returned automatically as previously set forth. In this improvement on my previous invention one of the grooves, 3,— 4,— is deeper than the other, forming a larger interior circumferential rib 120 than the opposite one.

The spool, C, has end flanges, c^x, of greater depth than shown in the other figures, upon one of which is pivoted a swinging cover, C², having slot, 5, through which the ribbons will 125 pass when inclosed by said cover; upon opposite flange, c^x, is sliding ring, c³, which is

slid over extension, 6, of said cover and will maintain it locked over the ribbons wound on spool, C.

After the ribbons are wound around the 5 spool an end cap, 7, is placed over one flange, c^x , whereby the diameter of said flange is greater than opposite end flange. Said cap is apertured at its end into which is inserted a rubber plug, 8, which securely locks this 10 end of the spool.

When a single ribbon is used, an end rod, 9, is attached thereto which limits its passage through slot, 5. When a number of overlying ribbons are used it is preferable that there 15 be one or more short pins, 10, on said rod, in order to confine each ribbon flatly in book form without risk of edges of any being curled during passage through slot, 5.

The spool with attachments, as set forth, 20 with cover C^2 , locked in position, is inserted within end of case, A, that has the small inverted groove and pushed there through until the enlarged head disk reaches opposite enlarged groove, which extends deeper within 25 said tube, and against which the enlarged head of spool with described attachments will abut and progress no farther.

The open ends, a, may be provided with pen, pencil, eraser or any suitable device.

30 In Fig. 11, I have not shown any spring, as I do not confine myself in said form to employment thereof. The tube A and its inclosures may be inserted in a cavity formed in a cane or any suitable article as illustrated in 35 the drawings or clamped thereon. See Figs. 4, 5, and 6.

By my improved device I provide novel, useful means for a convenient portable encyclopedia that will be found very useful for 40 many purposes.

Having thus fully described my invention and the manner of its operation, what I claim, and desire to secure by Letters Patent of the United States of America, is—

45 1. An incasement of the character described consisting of tube, A, divided into sections by circumferential grooves, 3,— 4,— provided with hollow interior revoluble spool, C', having apertured flange, c, at its opposite ends 50 said spool supplied with inclosed elasticspring extending the full length thereof, in combination with removable disks, C', provided on their outer surface with inverted grooves, c^2 , as and for the purpose intended, substantially 55 as described.

55 2. In a pen and pencil of the character described the tubular incasement, A, supplied with inner revoluble spool, C, in which is inclosed solid elastic spring, D', the perimeter 60 of which in cross section is polygonal, said spring having central apertured extension d, and end flanges, d', adapted to engage removable disks, C', conformed to interlock with

said flanges, in combination with one or more inscribed ribbons connected to said spring by 65 loop, b, as and for the purpose intended, substantially as described.

3. In a device of the character described open ended tubular incasement A, divided into sections, x , x , x' by circumferential 70 grooves, 3,— 4,— one of which projects within said tube deeper than the opposite one, the tube, A, having open ends, a, to receive pen, pencil, or analogous reversible instrument, the tube supplied with interior revoluble 75 spool, C, with interior spring attached by inelastic loop, b, to one or more ribbons, of inscribed fabric, B, in combination with spring controlled movable end disks, C', located inside encasement, A, and maintained at required distances apart by engagement of said disks with inwardly extending circumferential beads, formed by grooves, 3,— 4,— substantially as described.

4. In a device of the character described, a 85 multiple of overlying inscribed ribbons, B, B', upon the face of one or more of which is open pocket, P, the outer ribbon having end rod, 9, supplied with short projecting pins, 10, the opposite ends of said ribbons being 90 confined by binding strip, b', through which is passed inelastic loop, b, and described means for coiling said ribbons within tubular incasement, A, substantially as described.

5. In a device of the character described, 95 revoluble spool, C, having end flanges, c^x , to one of which is pivoted curved cover, C^2 , with lengthwise slot, 5, said cover having end extension, 6, adapted to be interlocked on opposite flange by sliding ring, c^3 , end cap, 7, in 100 combination with tubular, incasement, A, having inwardly extending grooves, 3,— 4,— of diverse diameter that limit progression of spool, within said incasement substantially as described.

6. The open ended incasement, A, divided into end sections, x , x , and central section, x' , by inwardly projecting circumferential grooves, 3,— 4,— slot, 5, lengthwise of section, x' hollow revoluble spool, C, having integral 110 apertured end flanges, c, inserted within central section, x' , elastic spring extending lengthwise within bore of the spool, the opposite ends of said spring engaging grooves, c^2 , of removable disks, C', in combination with 115 ribbons, B, connected by inelastic loop, b, to said interior spring as and for the purpose intended, substantially as described.

In testimony that I claim the invention above set forth I affix my signature in presence 120 of two witnesses.

SAMUEL L. LAZARON.
